(57) **CLAIM**

The ornamental design for a sacroiliac surgical guide, as shown and described.

DESCRIPTION

FIG. 1 is a perspective view of a sacroiliac surgical guide, showing our new design;

FIG. 2 is a front elevation view of the sacroiliac surgical guide illustrated in FIG. 1;

FIG. 3 is a rear elevation view of the sacroiliac surgical guide illustrated in FIG. 1;

FIG. 4 is a right elevation view of the sacroiliac surgical guide illustrated in FIG. 1;

FIG. 5 is a left elevation view of the sacroiliac surgical guide illustrated in FIG. 1;

FIG. 6 is a top plan view of the sacroiliac surgical guide illustrated in FIG. 1; and,

FIG. 7 is a bottom plan view of the sacroiliac surgical guide illustrated in FIG. 1.

The broken lines shown in the figures are included for the purpose of illustrating portions of the sacroiliac surgical guide and form no part of the claimed design.
